[57] CLAIM

The ornamental design for an egg display stand, as shown and described.

DESCRIPTION

FIG. 1 is a top perspective view of an egg display stand showing my new design;

FIG. 2 is a bottom perspective view, the stand having been inverted to an alternate position for use;

FIG. 3 is a top plan view;

FIG. 4 is a bottom plan view;

FIG. 5 is a front elevational view, the rear being a mirror image thereof; and,

FIG. 6 is a side elevational view, the stand having been inverted to an alternate position for use and the opposite side being a mirror image thereof.

FIG. 1

FIG. 2

FIG. 3
